UNITED STATES PATENT OFFICE.

JESSE H. HOLMES, OF ST. LOUIS, MISSOURI.

PAPER AND OTHER BAGS.

SPECIFICATION forming part of Letters Patent No. 258,925, dated June 6, 1882.

Application filed February 14, 1882. (Model.)

To all whom it may concern:

Be it known that I, JESSE H. HOLMES, of St. Louis, Missouri, have made a new and useful Improvement in Paper and other Bags, of 5 which the following is a full, clear, and exact description, reference being had to the annexed drawings, making part of this specification, in which—

Figure 1 is a side elevation of the improved 10 bag; Fig. 2, an edge sectional elevation; and Fig. 3, an edge sectional elevation, the folds of the bag being opened; and Figs. 4, 5, 6, 7, views illustrating the construction heretofore in use.

15 The same letters denote the same parts.

The present invention is an improvement more particularly in such as flour-bags, upon which it is customary to imprint inscriptions. The bags referred to commonly have what is 20 styled the "satchel-bottom," the construction of which is indicated in Figs. 4, 5, 6, 7, Figs. 4 and 5 being respectively a side and an edge sectional elevation of the bag before the final fold of the bottom is made, and Figs. 6 and 7 25 being respectively a side and an edge sectional elevation of the completed bag—that is, the fold *a* of the bottom *A* of the bag is finally turned upon the outside, *b*, of the body *B* of the bag, as seen in Figs. 6, 7. Now, with the class 30 of bags under consideration, it is desirable to have the inscription appear not only on the side of the bag near the bottom, but also on the bottom of the bag; but when the bag is folded, as described, the fold *a* comes above 35 or over the lower end of the side of the bag, and where it is desirable to have a portion of the inscription, for the brands which are demanded by the trade cover all the available space upon the side of the bag, extending from 40 the extreme upper end thereof, after allowing for the tying, to the extreme lower end there-

of, and considerably below where the fold *a* comes. Hence, that portion *c* of the inscription *C* that is to appear on the side of the bag necessarily has to be printed at a different 45 time from that *c'* appearing on the bottom of the bag. This materially increases the cost of the bag, and to obviate this difficulty, and enable the entire inscription to be printed at a single impression, is the aim of the present improvement, which consists in the manner of completing the bag at the lower end thereof prior to its being printed.

D, Figs. 1, 2, 3, represents the improved bag, and, saving the improvement, being of the customary description. The fold *d* of the bottom *d'*, however, in place of being upon the outside, *d''*, of the side *d³* of the bag, is tucked inside thereof, coming between the side *d³* and the side *d⁴*. Thus made, the extreme lower 60 end of the side *d³* is folded inward, and the fold *d⁵* of the bag projects beyond the lower end of the folded side *d³*, and the lower end, *d⁶*, of the folded side *d³* is exposed equally 65 with the fold *d⁵*, and the portion *e* of the inscription *E* can be imprinted on the bag at the same time as the portion *e'*.

The inscription on the bag-bottom is mainly for the purpose of indicating the contents of the bag when the latter is arranged endwise 70 to the observer on a shelf or in a pile.

I claim—

As a new manufacture, the bag *D*, having the part *d'* of the bottom between the sides *d³* *d⁴*, the side *d³* being folded inward at its lower 75 end, and the side *d⁴* projecting beyond the folded side *d³*, substantially as shown and described.

JESSE H. HOLMES.
